UNITED STATES PATENT OFFICE.

CHARLES SEARS, OF SOUTH EVANSTON, ILLINOIS.

GAME APPARATUS OR TOY TARGET.

SPECIFICATION forming part of Letters Patent No. 289,032, dated November 27, 1883.

Application filed August 25, 1883. (No model.)

To all whom it may concern:

Be it known that I, CHARLES SEARS, a citizen of the United States, residing in South Evanston, in the county of Cook and State of Illinois, have invented a new and useful Improvement in Game Apparatus or Toy Targets, of which the following is a specification.

My invention relates to certain improvements in toy targets and balls or projectiles for playing games.

In my invention the target is provided with a number of different-colored rings, preferably four in number—as, for example, yellow, red, white, and blue—around a gold center. 15 The surface of the target is covered with a number of sharp points made by driving wire nails or tacks through the disk upon which the colored rings are painted or pasted. These points serve to retain the ball or projectile 20 when it is thrown or shot against the target. The balls are preferably four in number, and may be colored—one yellow, one red, one white, and one blue—to correspond in color with the rings. The diameter of the ball is 25 greater than the distance between the sharp points on the target, so that the ball cannot be projected against the target without striking one or more of the points and sticking fast. The balls consist of a wooden center surrounded with wax or like plastic material and enclosed in a fibrous cover, so that the short points on the target will readily penetrate the balls when thrown against the target. The balls may be thrown by the hand or shot from 30 an air, spring, or other gun, as may be preferred.

In playing the game which I have invented as being specially adapted for use with my toy target and balls, if one of the balls or projectiles strikes the center or gold it counts twenty; the yellow ring, ten; the red ring, five; the white ring, three, and the blue or marginal ring two. If the color of the ball corresponds with the color of the ring it strikes on the target, it counts double. If the yellow ball strikes the gold center, it counts game. A flush, which consists in striking every color with its corresponding ball, also counts game. If any ball rests upon two colors at the same time, the 45 smaller number is to be counted. The game may be played in the parlor or hall. The

game may consist of one hundred points or other suitable number.

In the accompanying drawings, which form a part of this specification, and in which similar letters of reference indicate like parts, Figure 1 is a plan view of a device embodying my invention. Fig. 2 is a central section of one of the balls or projectiles, and Fig. 3 is a detail cross-section of the target through one of the sharp wires or points.

In the drawings, A represents the target-disk, preferably made of wood. B represents the center, which may be of a gold color; C, the yellow ring; D, the red ring; E, the white ring, and F the blue ring surrounding the center. These or other suitable-colored rings may be formed by painting the disk A, or by pasting over said disk a suitably-colored disk of paper, a. The face of the target is covered with a number of projecting sharp points, b. These sharp points b may be preferably formed by driving sharp-pointed nails or tacks through the wood disk A from its back. The heads of these nails may then be covered by 70 a disk of paper or other suitable covering, a', pasted over the back of the disk A. The balls c, d, e, and f are colored yellow, red, white, and blue, respectively, to correspond with the colors of the rings C, D, E, and F. 75 Each of the balls consists of a wood or other firm interior, g, a wax or other easily-penetrable substance, g', surrounding said center, and a fibrous or cloth covering, g'', incasing the same. Strings may be attached to the balls 80 for recovering the same in case the target should be missed. The soft or wax exterior of the balls serves to prevent their doing injury to objects which they may strike, as well as cause them readily to adhere to the sharp 85 points of the target. The wax shell surrounding the wood center of the ball serves to make the ball dead or inelastic, so that it will have no rebound when it strikes the points on the target. The function of the wood center is to 90 preserve the shape and form of the ball and prevent its flattening out, and of course it will be understood that other firm material may be used in place of the wood for the center of the balls. As the balls or projectiles stick wherever they strike on the points of the target, 95 they serve as their own markers and without 100

puncturing or injuring the target, and not rebounding from the target, they, of course, may be easily and quickly collected.

I claim—

- 5 1. The combination, with the target A, provided with sharp points b , of the balls or projectiles consisting of solid center g , annular shell g' , surrounding the same, made of soft or easily-penetrable material, and fibrous covering g'' , substantially as specified.
- 15 2. The target A, provided with center B and different-colored rings C, D, E, and F, and provided with sharp points b , substantially as specified.
- 15 3. The target-ball consisting of a wood or solid center, a shell surrounding the same, made of wax or other soft penetrable material,

and a fibrous covering, substantially as specified.

4. In playing games with targets, the use of 20 a number of different-colored balls, corresponding in color with the colors of the rings upon the target, the coincidence of the ball striking rings of like color making variations in the count, substantially as specified. 25

5. The combination, with a target having its surface provided with points, of a non-elastic soft projectile adapted to stick on the points of the target where it strikes, substantially as specified.

CHARLES SEARS.
